INTERNAL-COMBUSTION ENGINE

Joseph S. Parenti, Buffalo, N. Y.

Application November 16, 1942, Serial No. 465,644

17 Claims. (Cl. 123—56)

1

This invention relates to internal combustion engines.

One of the objects of this invention is to provide an internal combustion engine of improved construction.

Another object of this invention is to provide an engine of this type with cylinders of improved and simplified construction. A further object of this invention is to provide an engine of this type having the heads thereof formed integral with the cylindrical portions thereof. A further object of this invention is to provide an engine frame having cylinders mounted thereon for expansion and contraction independently of the engine frame. A further object is to provide the engine frame with jackets for a cooling fluid and extending about the cylinders, and with flexible heads which permit the cylinders to expand and contract with changes in temperature.

It is also an object of this invention to provide an engine frame or housing having cylinders with integral heads mounted therein and to provide the engine frame with flexible heads of light metal spaced from the cylinder heads to form a jacket for cooling the fluid, the flexible heads of the engine frame compensating for expansion and contraction of the cylinders.

It is also an object of this invention to provide an engine of this type of novel construction, in which the two opposed pistons may be inserted into the engine frame and after their cylinders have been assembled thereon.

A further object of this invention is to provide an improved mechanism for connecting the pistons of the engine with the shaft in such a manner that the piston is never in dead center relation to the shaft. Another object of this invention is to provide an engine of this type in which the pistons are connected to the shaft by means of oscillatory rocker arms which are intermittently coupled to and uncoupled from the shaft. A further object is to provide accurate and reliable means for connecting a rocker arm to the shaft during a fraction of each rotation of the shaft and to disconnect the rocker arm from the shaft during another fraction of the rotation thereof. It is also an object of this invention to provide the rocker arms with gear teeth which mesh with pinions on the shaft, which pinions are alternately rotated about their axes and held against such rotation. A further object of this invention is to provide improved means for alternately holding the pinions against rotation about their axes and releasing them.

A further object of this invention is to provide

2

an engine having a pair of opposed pistons which are alternately coupled to the shaft so that either piston is always securely coupled to the shaft, the pistons also being secured to each other. A further object is to provide a coupling mechanism for the engine by means of which the pistons may be reciprocated in their cylinders by rotation of the engine shaft. It is also an object of this invention to provide a coupling mechanism for an engine which causes the pistons to be moved through their entire strokes when the shaft is turned.

Other objects and advantages of this invention will appear from the following description and claims.

In the accompanying drawings:

Fig. 1 is a longitudinal central sectional elevation of an internal combustion engine embodying this invention.

Fig. 2 is a longitudinal elevation thereof, partly in section, and taken at a right angle to the view shown in Fig. 1.

Fig. 3 is a longitudinal sectional view thereof, on line 3—3, Fig. 2.

Fig. 4 is a transverse sectional view thereof, on line 4—4, Fig. 3.

Fig. 5 is a fragmentary transverse section thereof, on line 5—5, Fig. 1, on an enlarged scale.

Figs. 6 and 7 are fragmentary sectional elevations thereof, taken respectively on lines 6—6 and 7—7, Fig. 5.

Fig. 8 is a diagrammatic view showing the cam portion of one of the gear shafts and a portion of the cam plate with which it cooperates, for alternately locking and releasing its gear against and for rotation about its axis.

The engine shown in the drawings incorporates one embodiment of this invention and is of the two-cycle type having opposed cylinders in which two pistons 10 and 11 are arranged to reciprocate, the pistons being securely fastened together. These pistons are arranged to reciprocate respectively in the cylinders 12 and 13 which, in the particular construction shown, are made of relatively thin metal and provided with integral heads 14. These cylinders are securely fastened to an engine frame or housing 15, which may be of any suitable or usual construction, and which may be provided with intake passages or openings 16, which register with corresponding openings 17 in the cylinders 12 and 13. The intake openings 16 and 17 are preferably connected with suitable means for supplying air under pressure to the cylinders at the ends of their power strokes to scavenge the burnt gases

from the pistons, and since such means are well known, they are not shown in the drawings. The engine frame is also provided with discharge or exhaust openings 19, which are in registration with exhaust openings 20 formed in the engine cylinders 12 and 13.

The engine cylinders with their integral heads are formed separately from the engine frame and may be of a different metal or alloy from that of which the engine frame is made. The cylinders may be secured to the engine frame in any suitable or desired manner, and in the construction illustrated, portions of the cylinders remote from the heads are provided with screw threads 22 which engage correspondingly threaded portions of the engine frame. The engine cylinders may also be provided with stop shoulders or flanges 23 at which the threads terminate and which engage with shouldered portions of the engine frame to correctly position the cylinders on the engine frame.

As a result of this construction, it will be noted that the heads of the cylinders and large portions of the cylindrical walls thereof are spaced from the frame 15 of the engine in such a manner as to provide jackets 25 for a cooling fluid which may be circulated in any suitable or desired manner (not shown), and the engine frame may also be provided with additional jackets 26 extending about the threaded portions of the frame and cylinders. Consequently, the portions of the cylinders which become heated to the greatest extent during the operation of the engine are entirely out of contact with the engine frame and are in direct contact with the cooling fluid.

The heads of the cylinders may be provided with suitable threaded holes to receive spark plugs 28 and fuel injection nozzles 29, the latter receiving fuel under pressure from a conduit or tube 30 connected with suitable fuel supply means (not shown). The apertures in the cylinder heads for the spark plugs and fuel injection nozzles may be surrounded by annular flanges or bosses 31, the purpose of which will be more fully explained. These bosses preferably have outer portions 32 of reduced diameters.

It will be obvious that because of the mounting of the cylinders 12 and 13, the outer or head portions of these cylinders will during the operation of the engine become heated to a much greater extent than the walls of the engine frame which surround these outer portions of the cylinders, and consequently, the cylinders will expand outwardly to a greater extent than the adjacent portions 34 of the engine frame which extend about the outer portions of the cylinders. For this reason, the open ends of the portions 34 of the engine frame are provided with heads or closure disks which are sufficiently flexible to compensate for the difference in expansion between the cylinders and the adjacent parts 34 of the engine frame.

Any suitable flexible closures for the engine frame may be provided, and in the construction shown, I have provided closure disks 35 which are made of relatively thin metal of a nature which will permit flexing of these disks to the extent required by the expansion and contraction of the cylinders. These disks are secured to the open ends of the parts 34 of the engine frame in any suitable manner, for example, by means of bolts or screws 36, and gaskets 37 are provided to form fluid-tight connections between the disks 35 and the parts 34 of the engine. The closure disks are provided with holes through

which the ends 31 of the bosses or flanges 30 can pass, and fluid-tight connections are provided between the disks 35 and these bosses or flanges. This is done in the construction illustrated by screw threads on the parts 31 of these bosses, with which nuts 38 cooperate, and suitable packing washers 39 are provided which are compressed when the nuts 38 are tightened. The disks 35 of the engine frame may be provided with bulged out middle portions which ensure ample space between the cylinder heads 14 and the disk 35 of the engine frame for the circulation of cooling fluid. Since the closure disks 35 are only required to withstand the pressure of the cooling fluid circulated in the jackets of the engine, they can be made of relatively thin material, which in turn facilitates the flexing of these disks.

The pistons 10 and 11 may be of any suitable or usual construction, those shown having their outer or head portions rounded or bulging to extend into the correspondingly rounded or bulging head portions 14 of the cylinders. Each piston is preferably provided with means for deflecting air entering the inlet 16 toward the head of the cylinder, such for example as a grooved or recessed zone or part 42 at the peripheral portion of the head of the piston. This air deflecting groove functions when the piston is in the exhaust position, as the one shown in the right-hand side of Fig. 1, and results in thoroughly scavenging the burnt gases out through the exhaust port 19, and prevents the air entering through the intake 16 from passing directly across the cylinder to the exhaust port 20. Any other means for accomplishing this result may be employed.

The two pistons 10 and 11 are rigidly connected to each other in any suitable manner. For example, inner portions of the pistons may be provided with bifurcated extensions, each forming a pair of legs 43, the inner ends of which have flanges or lateral extensions 44 and 45, the adjacent end faces of which may be secured to each other. These flanges may be provided on their end faces with interfitting shoulders 46 formed so that the two pistons will be positioned in correct relation to each other. The flanges are provided with apertures through which bolts 47 may pass for securing the pistons together.

The bifurcated extensions of the pistons also receive between them the shaft 50 of the engine and these extensions of the pistons are, consequently, of sufficient length so that the pistons 55 may reciprocate in their cylinders without interfering with the centrally located shaft 50 or the parts mounted thereon.

In order to provide access to the pistons and to the interior of the engine frame, this frame is provided at opposite sides thereof with holes or openings which are closed by means of suitable plates or removable closure members 52 which may be bolted or otherwise secured to the engine frame about the openings therein. These plates or closure members also provide bearings for the shaft 50, the bearings being formed by means of cylindrical portions or extensions 53 of the plates 52. The openings closed by the plates 52 are made of a size large enough to permit the pistons to be inserted and withdrawn one at a time. In order to remove the pistons from the engine, the shaft 50 is first removed and the pistons are then separated from each other by removing the bolts 47. One of the pistons is then moved as far as possible toward the head of its cylinder, and the

other piston is moved partly into its cylinder and then turned about its axis through about 90 degrees so that the legs 43 of the bifurcated portion thereof can pass between the legs 43 of the other piston, thus permitting the first piston to be moved sidewise out of either one of the openings in the side of the engine frame or housing. The other piston is then withdrawn from its cylinder into a position to be moved sidewise from the opening in the engine frame.

In order to transmit the motion of the pistons to the shaft, a pair of rocker arms 55 and 56 are provided which extend in opposite directions from the shaft and which are mounted to oscillate about the axis of the shaft, the rocker arms being mounted on the shaft, one in advance of the other lengthwise of the shaft. The outer ends of these rocker arms may be connected with the pistons in any suitable or desired manner, so that the straight line motion of the pistons is transferred to the rocker arms, the ends of which move in arcs of a circle. In the construction shown, the legs 43 of the bifurcated extensions of the pistons are slotted, as indicated at 57, to receive the rocker arms. The inner ends of the bifurcated extensions of the pistons or the legs 43 are provided at their meeting faces with registering semi-cylindrical recesses in which bearings 58 may be arranged for the end portions 59 of connecting or eccentric pins. These pins have cylindrical portions 60 which are eccentric with reference to the end portions 59 of the connecting pins. These larger cylindrical portions 60 are arranged in suitable bearings 61 provided in the ends of the rocker arms 55 and 56. By means of this construction, the straight line movement of the pistons may be converted into oscillatory swinging motion of the outer end of the connecting rods. Any other means for transmitting motion of the pistons to the connecting rods may be employed.

The rocker arms 55 and 56 are intermittently connected with the shaft 50 in such a manner that during the power stroke of the piston 10, the rocker arm 55 will be connected with the shaft 50. Since during the power stroke of the piston 10, the piston 11 passes through its compression stroke, the other rocker arm 56 will be disconnected from the shaft 50. Similarly, when the piston 11 moves through its power stroke, the rocker arm 56 will be coupled to the shaft 50 and the other rocker arm 55 will be disconnected therefrom. Any suitable or desired mechanism may be provided for this purpose, and one example of a mechanism of this type will be described. To facilitate the understanding of this mechanism, the rocker arm 55 may be considered as cooperating with the piston 10 and the rocker arm 56 as cooperating with the piston 11.

In the operation of the engine as thus far described, it will be noted that the pistons when starting through their power stroke transmit their power to the rocker arms while the same are at an angle of about 60 degrees from what would be the dead center position in engines as now commonly constructed. Consequently, in such prior engines, the explosion in a cylinder takes place approximately when the piston is in dead center position, and consequently, when the gas pressure in the cylinder is at its maximum, the piston is still so near its dead center position that it is able to deliver comparatively little torque to the shaft, and most of this pressure and the shock resulting from the explosion must be absorbed and taken by the crank shaft and

bearings. Consequently, in engines as now commonly employed, when the maximum pressure is exerted on the piston, which is generally near the dead center position, comparatively little of this power is converted into turning movement on the crank shaft, and when the piston reaches a position at which its piston rod is nearly at a right angle to the crank, in which position it can deliver the maximum torque to the shaft per unit of pressure in the cylinder, this pressure in the cylinder has very materially decreased. By means of the construction shown in the drawings, however, the pistons never occupy positions anywhere near dead center with reference to the shaft 50, and consequently, when a piston is subjected to the maximum pressure, a large proportion of this pressure is available for turning the shaft. For example, in Fig. 1, the piston 10 is in position to begin its power stroke and the explosive mixture in the cylinder has been ignited. The force tending to move the piston 10 to the right in Fig. 1, consequently, delivers power to the rocker arm 55 while the same occupies the position shown in Fig. 1, which is about 30 degrees from a plane of the shaft 50 extending transversely of the pistons and the movement of the rocker arm 55 stops when the same has swung to a position 30 degrees at the opposite side of this plane. Consequently, in this engine, the dead center positions and all positions located within 60 degrees of the dead center position are eliminated, and the pistons thus act on the shaft in a highly advantageous manner so that a very efficient transmission of power from the pistons to the shaft results. While the rocker arms 55 in the construction illustrated in the drawings move through angles of 60 degrees, it will be obvious that it is not intended to limit this invention to engines operating at angles of 60 degrees, since any angle of movement of the rocker arms may be provided, of which 360 degrees is the multiple. It will be noted that, in the construction illustrated, for each revolution of the shaft, the pistons must make three reciprocations.

The mechanism herein illustrated by way of example for alternately coupling and uncoupling the rocker arms from the shaft is constructed to positively connect one of the two rocker arms to the shaft while one piston is moving through its power stroke and for positively disconnecting this rocker arm from the pistons while this piston is moving in the opposite direction, so that the rocker arms during the power strokes of the pistons will each impart rotation to the shaft in the same direction of rotation. In the construction shown for this purpose, the rocker arms are connected to the shaft by means of gears which are locked against rotation while the rocker arm moves in a direction to transmit power to the shaft, and are released for turning when the rocker arm is moved in the reverse direction. For this purpose, the portion of each rocker arm which extends about the shaft is provided with internal gear teeth 65 which mesh with one or more pinions 66, three such pinions being shown in the drawings. These pinions are rotatably mounted in the shaft 50. For this purpose, the shaft 50 is preferably made in two parts, which terminate near the longitudinal center line of the engine and the adjacent ends of these shafts are provided with annular enlargements 67 and 68. The peripheral portions of the flanges or enlargements 67 and 68 are recessed to receive the portions of the rocker arms 55 and 56 which ex-

tend about the shaft, and to space these rocker arms from each other, I preferably employ a spacer or partition plate 69 which is placed between the adjacent ends of the flanges or enlargements and the peripheral portions of which extend between the two rocker arms 55 and 56. End thrust bearing rings 69a are preferably provided at the outer faces of the annular portions of the rocker arms 55 and 56. Any suitable means may be provided for connecting the two flanges or enlargements of the two parts of the shaft 50, such for example as bolts or screws 70, and one of the two parts of the shaft 50 may be provided with a central or axial stud or integral projection 72 which extends into an accurately formed axial hole in the other part of the shaft, so that the two parts of the shaft will be accurately aligned axially.

The pinions 66 are provided with shafts 74 which are suitably journaled in the flanges 67 and 68 of the shaft, for example, in bearings 75 formed in these flanges, one set of pinions being provided for each flange. Preferably, additional bearing supports are provided for the pinions, this being done by means of bearing studs 76, Fig. 5, which are preferably secured to the spacing plate or disk 69 and these studs enter into holes bored coaxially into the shafts 74 with the pinions 66. The pinions 66 are preferably arranged in pairs which are in axial alignment with each other, one pinion of each pair meshing with the internal gear teeth of one of the rocker arms, and the other pinion cooperating with the other rocker arm, and consequently, each stud 76 may enter into the adjacent ends of two pinions, one of which pinions is journaled in the flange 67, the other pinion being journaled in the flange 68.

The outer ends of the shafts 74 connected with the pinions 66 are provided with cams 78 which, in the construction shown, are integral with the pinions and their shafts 74 and these cams are arranged to cooperate with stationary cam plates 80 which, in the construction shown, are secured to the stationary closure members 52 of the engine frame, for example, by means of bolts or screws 81. These stationary cams have cylindrical portions 82 which are concentric with the shaft 50 and between these cylindrical portions of the cams are recesses 83 extending inwardly from the inner peripheries of the cams. As clearly shown in Figs. 6 to 8, the cam portions 78 of the pinion shafts 74 are each provided with one face 84 which has substantially the same radius of curvature as the cylindrical portions 82 of the cam plate 80, so that the face 84 of each pinion cam 78 may engage with the cylindrical portions 82 of the stationary cam plate 80 and slide along these surfaces 82. It will be obvious that when the cam faces 84 and 82 are in sliding engagement, the pinions 66 will be held against rotation about their own axes, and when so held, the rocker arm connected with these pinions is coupled to the shaft 50 so as to transmit power thereto from an engine piston, or if the engine is being started or cranked by turning the shaft 50, power will be transmitted from the shaft to the pistons.

When the cam portion 78 of the pinion shafts move into positions at the cut-out portions 83 of the stationary cam plate 80, it will be obvious that the cam portions 78 then release their pinions 66, so that the same may rotate about their axes and this rotation causes the cam portions 78 of the piston shafts to swing into the recessed

portions 83 of the stationary cam as indicated by broken lines in Fig. 6.

Each of the two stationary cam plates 80 is so positioned relatively to the other stationary cam that when one set of pinions is held against rotation by the cylindrical portion 82 of one cam plate 80, the other set of pinions is free to rotate in a recessed portion 83 of the other stationary cam. In other words, when the pinion cams 78 of one set of pinions geared to rocker arm 55 are in sliding contact with the cylindrical portions 82 of one stationary cam plate so that these pinions are held against rotation, the other set of pinions geared to the other rocker arm 56 will be free to rotate, since their cams 78 will have slid along the cylindrical portions 82 of the cam plate so as to be in the recessed portions 83 of the other stationary cam. It will, consequently, be obvious that one of the two rocker arms 55 and 56 will always be coupled to the shaft 50, so that in the particular construction illustrated, in which the rocker arms swing in arcs of 60 degrees, each reciprocation of the pistons advances the shaft through 120 degrees.

The cam face 84 of the pinion shaft is preferably also provided with a cam groove or depression 87 which extends rearwardly from the axis of rotation 88 of the pinion shaft, see Fig. 8. This cam groove 87 is so formed that as the cam member 78 swings out of a recessed portion 83 of the stationary cam 80, the edge portion 89 of the stationary cam remains in contact with the surface of the cam groove until the cam surface 84 contacts with the concentric or cylindrical face 82 of the stationary cam. 90 represents the axis of the shaft 50 in Fig. 8.

In the operation of the mechanism described, it will be noted that as a rocker arm begins its return swing during the compression stroke, of its piston, the cams 78 of the three pinion shafts connected with this rocker arm begin their rotation within the recesses 83. As the rocker arm approaches the end of its compression swing, the edge portion 89 of the stationary cam enters the groove 87 before this swing of the rocker arm is completed. If there should be a tendency of the piston not to return to its outermost position, or in other words, if the piston tends to stop before it has reached the intended end of its compression stroke, then pressure will be exerted by the edge portion 89 against a portion of the groove 87 to turn the cam 78 into position to have its face 84 lie on the cylindrical face 82 of the stationary cam. This pressure will increase as the edge 89 engages parts of the groove 87 further removed from the center of rotation 88 of the pinion shaft and will force the piston into its outermost position. If the piston tends to move beyond this position, then it will be stopped at its outermost position by the engagement of the face 84 of the cam 78 with the cylindrical portion 82 of the stationary cam. Other means for coupling and uncoupling the rocker arms to and from the shaft may be provided.

The engine may be lubricated in any desired manner, no lubricating means being shown in the drawings. Also any suitable means may be provided for directing a cooling fluid through the jackets of the engine and for cooling any parts of the engine requiring cooling, such means being omitted from the drawings to avoid confusion.

By means of the mechanism described, it will be obvious that the pistons will at all times be coupled to the shaft either through the rocker arm 55 or through the rocker arm 56, and this

coupling is positive so that the shaft 50 may be rotated for the purpose of starting or cranking the engine, and so that the shaft 50 will at all times be in synchronism with the pistons. This ensures the positive stroke of each piston so that uniform compression will result. Another advantage of this arrangement is that the timing mechanisms for fuel injection, ignition, etc., may be driven from the engine shaft, as has heretofore been customary in connection with crank shaft engines.

The engine described has the advantage that power generated in the cylinders by the combustion of the fuel will be transmitted to the shaft 50 much more efficiently than in engines heretofore in general use. As a result of this construction, a relatively short stroke may be employed, and the movement of the pistons will be more responsive to the pressures of the burning gases, since movement of the pistons will not be delayed by the crank shaft positions at and near dead center. The more rapid travel of the pistons and the shorter stroke will result in the discharge of the burned gases more rapidly so that less of the heat will be transmitted to the parts of the engine. As a result of these various features, the engine herein described is more efficient than engines of the type now commonly used.

It will, of course, be obvious that the coupling and uncoupling mechanisms herein described may be used in connection with engines of different construction from the one herein illustrated.

I claim as my invention:

1. An engine including a pair of oppositely disposed pistons rigidly connected with each other, a shaft, a pair of rocker arms extending in opposite directions from said shaft and each having one end thereof mounted to oscillate about said shaft and having the other end connected to said pistons, means for coupling one of said rocker arms to said shaft during the power strokes of one of said pistons and for coupling the other rocker arm to said shaft during the power stroke of the other piston, and means for uncoupling said rocker arms from said shaft during the compression strokes of their pistons.

2. An engine including a pair of oppositely disposed pistons having their adjacent ends bifurcated and secured together, a shaft extending through said bifurcated ends of said pistons, rocker arms mounted to swing about said shaft and extending in opposite directions therefrom and having their outer ends connected with said pistons, and coupling means for alternately coupling and uncoupling said rocker arms to said shaft, one rocker arm being coupled to said shaft when said pistons move in one direction and the other rocker arm being coupled to the shaft when said pistons move in the other direction.

3. An engine having oppositely disposed pistons and provided at their adjacent portions with oppositely spaced legs, means for securing the legs of one piston to the legs of the other piston for rigidly securing said pistons to each other, a shaft extending between the legs of said pistons, arms extending in opposite directions from said shaft and connected with said pistons to cause the reciprocatory motion of said pistons to alternately swing said arms in opposite directions about said shaft and in opposite directions to each other, and means for alternately coupling said arms to said shaft and uncoupling said arms from said shaft, one of said arms being coupled to the shaft while the other arm is uncoupled therefrom.

4. An engine having oppositely disposed pistons

and provided at their adjacent portions with oppositely spaced legs, means for securing the legs of one piston to the legs of the other piston for rigidly securing said pistons to each other, a shaft extending between the legs of said pistons, arms extending in opposite directions from said shaft and connected with said pistons to cause the reciprocatory motion of said pistons to alternately swing said arms in opposite directions about said shaft and in opposite directions to each other, and means for coupling said arms to said shaft when they move in the direction of rotation of said shaft and for uncoupling said arms from said shaft when they move in the opposite direction.

5. An engine having oppositely disposed pistons and provided at their adjacent portions with oppositely spaced legs, means for securing the legs of one piston to the legs of the other piston for rigidly securing said pistons to each other, a shaft extending between the legs of said pistons, rocker arms arranged about said shaft, one of said rocker arms being connected with said piston at one side of said shaft and the other rocker arm being connected with said piston at the other side of said shaft, to cause reciprocation of said pistons to swing said arms about said shaft, and means for operatively connecting one of said arms to said shaft during the power stroke of one piston and for operatively connecting the other arm to said shaft during the power stroke of the other piston, said means disconnecting said arms from said shaft when their pistons move in their compression strokes.

6. An internal combustion engine having opposed cylinders, a piston in each cylinder, said pistons being secured to each other, a shaft located intermediate of said pistons, and two connections between said shaft and said pistons, one connection being coupled with said shaft during the power stroke of one piston and the other connection being connected with said shaft during the power stroke of said other piston, said connections being uncoupled from said shaft when their pistons move through their compression strokes, and turning said shaft through less than one-half revolution during each power stroke.

7. An internal combustion engine including a frame, a pair of opposed cylinders mounted on said frame, pistons arranged to reciprocate in said cylinders and having the ends adjacent to each other bifurcated to form a pair of legs on each piston, means for securing said legs together, a shaft extending between said legs, a driving connection between said pistons and said shaft, said frame being provided with openings at opposite sides thereof, and closure members removably secured to said frame for closing said openings and having bearings for said shaft.

8. An internal combustion engine including a frame, a pair of opposed cylinders mounted on said frame, and having heads formed integral therewith, pistons arranged to reciprocate in said cylinders and having the ends adjacent to each other bifurcated to form a pair of legs on each piston, means for securing said legs together, a shaft extending between said legs, a driving connection between said pistons and said shaft, said frame being provided with openings at opposite sides thereof, of sufficient size to permit said pistons when separated from each other to be removed through said openings, and closure members removably secured to said frame for closing

said openings and through which said shaft extends.

9. An internal combustion engine having a pair of opposed pistons, a shaft, a pair of arms mounted to oscillate about said shaft and connected with said pistons to be oscillated thereby, and coupling means alternately positively connecting and disconnecting said arms from said shaft to transmit movement of the pistons to said shaft, whereby turning of said shaft produces reciprocatory movement of said pistons.

10. In an internal combustion engine, the combination of a pair of opposed pistons, said pistons having legs at the portions adjacent to each other and which are secured together to rigidly connect said pistons with each other, a shaft extending into said frame and passing between said legs, a pair of rocker arms arranged to oscillate about said shaft, one of said rocker arms extending from one side of said shaft and being connected for cooperation with one of said pistons and the other rocker arm extending from the other side of said shaft and being connected for cooperation with the other piston for oscillation of said rocker arms by the reciprocation of said pistons, and a cam actuated mechanism for alternately coupling said rocker arms to said shaft and for simultaneously coupling one rocker arm and uncoupling the other rocker arm, for transmitting power from said pistons to said shaft.

11. The combination with an internal combustion engine having opposed reciprocating pistons having spaced legs secured to each other, a shaft extending between said spaced legs, a pair of rocker arms mounted to oscillate about said shaft and extending from opposite sides of said shaft and connected with said pistons for oscillation of said rocker arms by said pistons, gears on said rocker arms concentric with said shaft, pinions journaled on said shaft and meshing with said gears, and means for alternately stopping the rotation of said pinions about their axes and releasing them for said rotation, the pinions driven by one rocker arm being held against said rotation while one of said pistons is moving through its power stroke and the pinions driven by the other rocker arm being held against rotation when the other piston is moving through its power stroke, to transmit power from said rocker arms through said gears and pinions to said shaft during the power strokes of said pistons.

12. The combination with an internal combustion engine having opposed reciprocating pistons having spaced legs secured to each other, a shaft extending between said spaced legs, a pair of rocker arms mounted to oscillate about said shaft and extending from opposite sides of said shaft and connected with said pistons for oscillation of said rocker arms by said pistons, a gear fixed on each rocker arm, a pinion journaled on said shaft and meshing with one of said gears, and another pinion journaled on said shaft and meshing with the other gear, means for locking the pinion connected with one of said rocker arms against rotation while the pinion connected with the other rocker arm is free to revolve and while one of said pistons is moving through its power stroke, and means for reversing the locking and releasing of said pinions while the other piston is moving through its power stroke, whereby said pistons are at all times positively connected in driving relation to said shaft through said pinions when locked.

13. The combination with an internal combustion engine having opposed reciprocating pistons having spaced legs secured to each other, a shaft extending between said spaced legs, a pair of rocker arms mounted to oscillate about said shaft and extending from opposite sides of said shaft and connected with said pistons for oscillation of said rocker arms by said pistons, gears fixed on said rocker arms, pinions journaled on said shaft, one of said pinions meshing with the gear of one rocker arm and the other pinion meshing with the gear of the other rocker arm, cams cooperating with said pinions for alternately holding said pinions against rotation about their axes and for releasing said pinions to rotate about their axes, said cams being timed to cause one pinion to be locked while the other is released, a pinion being locked while the rocker arm connected therewith is actuated by the power stroke of one piston and the other pinion being locked while the other arm is actuated by the power stroke of the other piston.

14. The combination with an internal combustion engine having opposed reciprocating pistons having spaced legs secured to each other, a shaft extending between said spaced legs, a pair of rocker arms mounted to oscillate about said shaft and extending from opposite sides of said shaft and connected with said pistons for oscillation of said rocker arms by said pistons, said rocker arms being provided with internal gear teeth arranged in fixed relation thereto, pinions journaled on said shaft in eccentric relation thereto, one of said pinions meshing with the teeth of one rocker arm, and the other pinion meshing with the teeth of the other rocker arm, and cam means for alternately locking one pinion against rotation about its axis while the other pinion is free to rotate about its axis, said cam means being timed to lock the pinion connected with one rocker arm against rotation while one of said pistons moves through its power stroke and for locking the other pinion against rotation when the other piston moves through its power stroke, whereby said rocker arms are alternately coupled to said shaft through said gear teeth and pinion.

15. The combination with an internal combustion engine having opposed reciprocating pistons having spaced legs secured to each other, a shaft extending between said spaced legs, a pair of rocker arms mounted to oscillate about said shaft and extending from opposite sides of said shaft and connected with said pistons for oscillation of said rocker arms by said pistons, each of said rocker arms having a gear fixed thereto, pinions journaled on said shaft, in eccentric relation thereto, one of said pinions meshing with the gear of one of said rocker arms, and the other pinion meshing with the gear of the other rocker arm, a cam arranged in fixed relation to each of said pinions to rotate therewith, a pair of stationary cams, one of which cooperates with the cam of one of said pinions and the other of which cooperates with the cam of the other pinion, said stationary and pinion cams operating to intermittently lock said pinions against rotation about their axes and to release said pinions for rotation about their axes, said cams being timed to lock the pinion connected with one of said arms while one of said pistons moves through its power stroke and to lock the other pinion against rotation while the other piston moves through its power stroke.

16. An internal combustion engine having op-

posed cylinders, pistons arranged to reciprocate therein and secured to each other, a rotary shaft, a pair of arms arranged to swing about said shaft and extending in opposite directions therefrom and connected with said pistons to convert reciprocal motion of said pistons to oscillatory swinging motion of said arms, each of said arms having a gear arranged in fixed relation thereto, pinions journalled on said shaft to rotate about axes spaced from the axis of rotation of said shaft, one pinion meshing with one gear of one of said arms and the other pinion meshing with the gear of the other arm, each pinion having a cam rotatable therewith, a pair of fixed cams, one of said cams cooperating with the one of said pinions and the other cam cooperating with the other pinion, the faces of said stationary cams and of the pinion cams cooperating therewith being formed to hold said pinions against rotation about their axes while the arms geared thereto are moved by the power strokes of the pistons and to permit rotation of said pinions while the arms geared thereto are moved by the compression strokes of said pistons, and additional faces on said stationary and fixed cams which engage during rotation of said shaft, to rotate said pinions during the final portion of the movement of said pistons in their compression strokes in a direction to move said pistons through said portions of their compression strokes.

17. An internal combustion engine having opposed cylinders, pistons arranged to reciprocate

therein and secured to each other, a rotary shaft, a pair of arms arranged to swing about said shaft and extending in opposite directions therefrom and connected with said pistons to convert reciprocal motion of said pistons to oscillatory swinging motion of said arms, each of said arms having a gear arranged in fixed relation thereto, pinions journalled on said shaft to rotate about axes spaced from the axis of rotation of said shaft, one pinion meshing with the gear of one of said arms and the other pinion meshing with the gear of the other arm, each pinion having a cam rotatable therewith, a pair of fixed cams, one of said cams cooperating with one of said pinions and the other cam cooperating with the other pinion, the faces of said stationary cams and of the pinion cams cooperating therewith being formed to hold said pinions against rotation about their axes while the arms geared thereto are moved by the power strokes of the pistons, and to permit rotation of said pinions while the arms geared thereto are moved by the compression strokes of said pistons, a cam groove on each pinion cam arranged near and at one side of the axis of rotation thereof, and a projection on each stationary cam which enters said cam groove during the final rotation of the pinion cam to exert pressure on the pinion cam in a direction to positively force the pinion to complete its rotation and thereby ensure the movement of the piston connected therewith to the end of its compression stroke.
